UNITED STATES PATENT OFFICE.

GEORGE HOEPNER, OF CHICAGO, ILLINOIS.

LOOPER MECHANISM FOR SEWING-MACHINES.

1,270,948.

Specification of Letters Patent.

Patented July 2, 1918.

Original application filed October 27, 1916, Serial No. 128,104. Divided and this application filed August 15, 1917. Serial No. 186,257.

To all whom it may concern:

Be it known that I, GEORGE HOEPNER, a citizen of the United States, residing at Chicago, county of Cook, State of Illinois, 5 have invented a certain new and useful Improvement in Looper Mechanism for Sewing-Machines, and declare the following to be a full, clear, and exact description of the same, such as will enable others skilled in 10 the art to which it pertains to make and use the same, reference being had to the accompanying drawings, which form a part of this specification.

My invention has for its object to produce 15 a simple, powerful and efficient sewing machine adapted for a great variety of uses and particularly for heavy work.

A further object of the present invention is to produce a simple and novel looper.

20 The various features of novelty whereby my invention is characterized will herein-after be pointed out with particularity in the claims; but, for a full understanding of my invention and of its objects and advan- 25 tages, reference may be had to the following detailed description taken in connection with the accompanying drawings, wherein:

Figure 1 is a side elevation of a sewing machine head, with the side or cover re- 30 moved, containing a preferred embodiment of my invention;

Fig. 2 is a side elevation of the looper rod and looper, together with the swiveled bearing therefor;

Fig. 3 is a section taken approximately 35 on line 3-3 of Fig. 2;

Fig. 4 is a side view of the looper element detached from the supporting devices;

Fig. 5 is a diagrammatic view illustrating 40 a row of stitches made by the machine and one step in the process of making one of the stitches;

Fig. 6 is a diagrammatic view illustrating a second step in the process of making a 45 stitch; and

Fig. 7 is a diagrammatic view illustrating a third step in the process of making a stitch.

Referring to the drawings, 1 represents 50 a frame in the form of an inverted U across the yoke portion of which extends a horizontal driving shaft, 2. In the lower end of one of the arms of the frame is a horizontal reciprocable needle bar, 3, and the usual 55 presser foot bar, 4, between which and a

suitable work-engaging plate, 5, on the opposite arm of the frame, the work is held. In the frame above the needle bar is a bell crank lever, 6, between the lower long arm of which and the needle bar is a connecting link, 7. Between the upper short arm of the bell crank lever and the driving shaft, 2, is a connecting rod, 8, attached eccentrically to the end of the driving shaft by a universal joint, 9, and to the bell crank lever by 65 means of a clevis, 10, which affords movement about two axes at right angles to each other.

Mounted on the other arm of the frame is a work-feeding arm, 11, having a work-feeding element, 11a, pivotally supported between its ends so as to be rotatable about a pin, 12, parallel with the shaft 2 and about a second pin, 13, at right angles to the shaft 2. An eccentric, 14, arranged on the shaft 75 and engaging with the upper end of the arm 11 serves to oscillate it about the pin 12. A cam device, 15, acting on a cam roll, 16, carried by the upper end of the arm 11, combined with a spring, 17, serves to oscillate 80 the work-feeding arm about the pin 13.

At one side of the work-feeding arm is a vertical oscillatory reciprocable rod, 18, the upper end of which is connected to a crank, 19, formed in the driving shaft. Near its 85 lower end the rod passes slidably through a block, 20, pivotally connected at one side thereof to the frame by means of a bolt or screw, 21, passing through an opening, 22, in the block. It will be seen that as the driving shaft is revolved it reciprocates the rod 18 and at the same time oscillates it through a small angle; this oscillatory motion being permitted by the pivotal mounting of the block 20. The rod 18 is a looper rod and on its lower end carries a looper device adapted 90 to coöperate with the needle 23. The looper comprises a short tubular body portion, 25, having a downwardly extending flattened part, 26, provided in one face with a groove, 27, forming a continuation of the bore or passage in the tubular member and having in the point thereof an eye, 28. The looper 95 is held in a suitable head, 29, in such a manner as to permit it to stand approximately 100 vertically and have capacity for adjustment in the vertical direction; the head being in turn supported on the lower end of the rod 18 in such a manner as to permit it to be 105 turned angularly about the axis of the rod 110

and, if desired, be adjusted in the direction of the length of the rod. It will be seen that as the driving shaft revolves it causes the looper to rise and fall while at the same time it moves through a limited distance transversely to a vertical plane; this latter movement needing to be only great enough to permit the looper to travel across the top of the needle so as to enable it to come up 10 on one side of the needle, when the latter is in the work, and go down on the other side thereof.

The needle is threaded in the usual way and a thread, not shown, is also adapted to pass from a suitable source of supply through an eye in a stationary part, 30, arranged in proximity to the looper and thence down through the tubular member, 25, and through the eye, 28, of the looper.

20 Viewing the parts as they appear in Fig. 1, the needle being retracted, the looper is down and is traveling forward toward the observer, holding its thread, A, (see Fig. 5) through a loop, b, that the looper has just taken from the needle and carrying this loop forward toward the observer and laying it against the work, C. The work is now being fed away from an observer in Fig. 1 so that the loop, b, is being acted upon both 25 by the pulling force on the work and by the looper. When the looper reaches a position in front of the needle, the needle starts back toward the work, forming its thread, B, into a second loop, bb, which is carried toward 30 and into the work as indicated in Fig. 6. The loop bb passes underneath the loop b because the latter is being lifted by the looper at the same time that it is being lengthened or extended; this being due to 35 the fact that the looper is traveling upwardly while the needle is advancing into the work and while the looper is still moving in a direction to lengthen the loop. Fig. 7 shows the condition of the parts 40 just after the needle has started on its back stroke so as to cause the loop bb to open; the looper being just about to descend between the needle and its thread, namely through the loop bb which is then laid down 45 as the work is fed ahead until it takes position of the loop b in Fig. 5.

While I have illustrated and described more or less in detail a particular form of connection between the driving shaft and the 50 needle bar and a particular type of work-feeding device, such as illustrated in my prior application Serial No. 128,104, dated October 27, 1916, of which the present application is a division, the present invention 55 has to do only with my novel loop-forming mechanism considered by itself and as a part of a new type of sewing machine in which there is a single driving shaft parallel with the needle bar, together with three 60 separate members extending transversely of

the driving shaft and operating respectively the needle bar, the work-feeding element, and the looper.

I claim:

1. In a sewing machine, a driving shaft 70 having a crank therein, a reciprocable needle arranged parallel with said shaft, a looper rod connected at one end to said crank, a looper at the other end of said rod arranged in proximity to the path of said needle, and means for supporting said rod at a point between its ends in a manner to cause the looper to describe a path lying in a plane at right angles to the path of travel of the needle and passing entirely around the path of 80 travel of the needle.

2. In a sewing machine, a driving shaft having a crank therein, a reciprocable needle arranged parallel with said shaft, a looper rod connected at one end to said crank, a 85 looper carried on the other end of said rod in proximity to the path of travel of the needle, and means for slidably and pivotally supporting said rod between the ends thereof so as to permit the looper to travel down 90 past the needle on one side of the latter and then cross over to the opposite side of the path of the needle and travel upwardly far enough to permit the looper to clear the needle and enable the looper to return to the 95 starting point.

3. In a sewing machine, a driving shaft having a crank therein, a reciprocable needle arranged parallel with said shaft, a looper rod connected at one end to said crank, a 100 looper carried on the other end of said rod and having in the point thereof an eye for a thread, and means for supporting said rod at a point between its ends to permit the looper to carry its thread completely 105 around the path of travel of the needle in such time relation to the needle as to cause the needle thread and the looper thread to be interlocked in a stitch.

4. In a sewing machine, a reciprocable 110 needle bar, a rotary main drive shaft parallel with and at some distance from the bar, a connecting rod and lever mechanism between the shaft and the bar for actuating the same, an arm extending from the shaft 115 to a point adjacent to the line of travel of the needle bar, a work-feeding element on the arm at the latter point, a driving connection between the shaft and the arm, a looper rod extending from the shaft toward 120 the line of travel of the needle bar, a looper on said rod adapted to be moved across the line of travel of the needle bar, and a driving connection between the rod and the shaft.

5. In a sewing machine, a main driving shaft, a reciprocable needle bar parallel with the shaft, an oscillatory feeder arm and an oscillatory and reciprocatory looper rod extending transversely of said shaft; 130

a connecting rod and lever mechanism between said shaft and the needle bar for driving the latter; and driving connections between the shaft and the feeder arm, and 5 the shaft and the looper rod.

6. In a sewing machine, a main driving shaft, a reciprocable needle bar parallel with the shaft, an oscillatory feeder arm extending transversely of the shaft, a driving 10 connection between the shaft and said bar including a connecting rod and lever mechanism and a driving connection between the shaft and said arm.

7. In a sewing machine, a main driving 15 shaft, a reciprocable needle bar parallel with the shaft, an oscillatory and reciprocatory looper rod extending from said shaft toward the line of travel of the needle bar, a looper on said rod adapted to be moved

across the line of travel of the needle bar, 20 a driving connection between the shaft and the needle bar including a connecting rod and lever mechanism, and a driving connection between the shaft and the looper rod. 25

8. In combination, a looper rod, a head secured to one end of said rod and projecting laterally therefrom, said head being adjustable in the direction of the length of the rod and also angularly of the axis of 30 the rod, and a looper mounted in said head at some distance from the rod and lying approximately parallel with the rod, said looper being adjustable in the direction of its length and also angularly about its axis. 35

In testimony whereof, I sign this specification.

GEORGE HOEPNER.
